UNITED STATES PATENT OFFICE.

WILLARD C. JAMES, OF LOS ANGELES, CALIFORNIA.

FOLDING BED.

No. 800,374.

Specification of Letters Patent.

Patented Sept. 26, 1905.

Original application filed April 18, 1903, Serial No. 147,933. Divided and this application filed July 8, 1903. Serial No. 164,657.

To all whom it may concern:

Be it known that I, WILLARD C. JAMES, a citizen of the United States, residing at Los Angeles, in the county of Los Angeles and State of California, have invented a new and useful Improvement in Folding Beds, of which the following is a specification.

The present invention relates to a folding-bed construction and is in part a division of my application, Serial No. 147,933, filed April 18, 1903.

The main object of this invention is to provide for support and ventilation of the bed-clothing in a folding bed.

15 A further object is to provide a folding bed having certain desirable features of simplicity in construction and convenience in operation.

The accompanying drawings illustrate the invention.

20 Figure I is a vertical section of the bed in lowered position. Fig. II is a plan of the bed in raised position. Fig. III is an end view of the bed in lowered position, taken from the back of the headboard. Fig. IV is a side elevation of the bed in raised position. Fig. V is a detail view of the spring-clips serving as a bedding-retainer. Fig. VI is a detail section of an extensible leg or rest for the bed.

1 designates a suitable support or base 30 adapted to rest on the floor, as by means of casters 2, and extending to a height sufficient to support the hinges or trunnions 3 of the bed-frame 4. The front or under side of this frame may be formed as a pier-glass or otherwise ornamented.

35 Bed-frame 4 has near its outer end legs or rests desirably extensible, so as to enable them to reach the floor when the bed is down and yet not project inconveniently far when the bed is raised. Projections 5 on the front of the bed-frame have each a longitudinal recess or socket 6 formed therein, in which posts or strips 7 slide in and out. The outer end of the strip is of the same width as the recess, but 45 the inner end is of less width, which thereby forms a shoulder 8 in the side adapted to engage the lower or outer edge of the projection at the side of the recess 6, as shown in Fig. VI, a spring 9 opposite the shoulder 50 holding the strip over to one side to cause such engagement. Projections 5 may when the bed is raised constitute shelves on each side of the pier-glass.

At or near its outer end the bed-frame is 55 provided with posts or rack-supporting means

10, each of which is provided with a series of spring-clips 11, the clips of the two posts 10 arranged in pairs and the two clips of each pair being opposite and facing each other. These clips are preferably each formed by doubling a piece of resilient metal upon itself and inserting the doubled portion into a hole or recess 11 in the post with its outer or free ends in yielding engagement with each other. The inner ends of the clips are fastened in 65 their respective holes by passing a pin through the doubled portions, and the tips of the outer ends are slightly curved or bent away from each other to form a mouth or opening, as shown in detail in Fig. V, and adapted to receive 70 the bedclothes, which are each inserted in corresponding clips on opposite sides, and when the bed is raised to the position shown in Fig. IV the bedclothes will be held open or separate to provide for ventilation thereof. 75 Doors or hinged sides 12 are provided at each side of the bed-frame, these doors hanging down out of the way when the bed is lowered, as indicated in Figs. I and III. When the bed is raised, these doors are kept open awhile 80 to allow the bedclothes to ventilate and may then be shut to inclose or conceal the bed and bedclothes.

13 designates a pocket or receptacle formed at the outer end of the bed and adapted to receive 85 the pillow when the bed is not in use.

15 is the counterweight.

A headboard 14 may be fixed on the support in such position that when the bed is raised and the doors 12 are shut said board 90 will be inclosed or hidden thereby at each side. The back of the bed is, however, preferably left open and will generally be out of sight—as against a wall, for example.

What I claim, and desire to secure by Letters Patent of the United States, is—

1. A folding bed provided with posts at its free end, spring-clips secured in fixed position on the posts, said clips being arranged in pairs opposite one another to engage and retain the bedclothes, and the adjacent pairs of clips being separated to hold the bedclothes apart when so retained.

2. A folding bed provided with posts at its free end and spring-clips secured in fixed position on said posts, said spring-clips being arranged in pairs and facing each other, for engaging and retaining the bedclothes, and the adjacent pairs of spring-clips being separated to hold the bedclothes apart when so retained.

3. A folding bed provided with recessed posts at its free end, and spring-clips secured in fixed position in the recesses of said posts.
4. A folding bed provided with recessed posts at its free ends, spring-clips in the recesses and arranged to face each other.
5. A folding bed provided with recessed posts at the free end, spring-clips in the recesses, each clip consisting of a piece of resilient metal doubled upon itself and having its doubled portion secured in the recess and its free ends in yielding engagement, the clips of the two posts being opposite to and facing each other.
10. A folding bed provided with recessed posts at its free ends, spring-clips secured in fixed position on said posts, each clip being opposite the clip on the other post to form a pair of clips for the reception and retention of the bedclothes and each clip consisting of a piece of resilient metal doubled upon itself with its free ends in yielding engagement.
15. A folding bed provided with posts at its free ends, spring-clips secured in fixed position on said posts, each clip being opposite the clip on the other post to form a pair of clips for the reception and retention of the bedclothes and each clip consisting of a piece of resilient metal doubled upon itself with its free ends in yielding engagement.
20. A folding bed provided with posts, and spring-clips arranged on said posts in pairs and facing each other, each clip comprising resilient members with their ends in yielding engagement.
25. In a folding bed, a support, a bed-frame pivotally secured thereto at one end, recessed posts at the free end of the frame, and a spring-clip in each recess, said clips being arranged to face each other.
30. In a folding bed, a support, a bed-frame pivotally secured thereto at one end, recessed posts at the free end and a spring-clip in each
35. recess, each clip consisting of a piece of resilient metal doubled upon itself and having its doubled portion secured in the recess and its free ends in yielding engagement, the clips of the two posts being opposite to and facing each other.
40. 10. In a folding bed, a support, a bed-frame pivotally secured thereto at one end, the front of said frame being provided with a mirror and two flat shelf-like longitudinally-recessed projections, a shoulder-strip in each recess, and means for causing the shoulder to engage with the outer end of the projection and hold the strip projected.
45. 11. In a folding bed, a support, a bed-frame pivotally secured thereto at one end, the front of the frame being provided with two longitudinally-recessed projections, a strip in each projection, the inner end of which is of less width than the recess and of the outer end of the strip thereby forming a shoulder, and a spring in the recess on the side opposite said shoulder to face the strip laterally and cause the shoulder to engage with the outer end of the projection and hold the strip projected.
50. In testimony whereof I have signed my name to this specification, in the presence of two subscribing witnesses, at Los Angeles, in the county of Los Angeles and State of California, this 27th day of June, 1903.
55. WILLARD C. JAMES.
